UNITED STATES PATENT OFFICE.

WILLIAM H. CLARKSON, OF EDWARDS STATION, ILLINOIS, ASSIGNOR TO
ELUIDE J. CLARKSON, OF EDWARDS STATION, ILLINOIS.

SUPPORT FOR COAL-DRILLS.

No. 825,113.

Specification of Letters Patent.

Patented July 3, 1906.

Application filed January 30, 1905. Serial No. 243,299.

To all whom it may concern:

Be it known that I, WILLIAM H. CLARKSON, a citizen of the United States, residing at Edwards Station, in the county of Peoria and State of Illinois, have invented certain new and useful Improvements in Supports for Coal-Drills; and I do hereby declare that the following is a full, clear, and exact description of the invention, which will enable others skilled in the art to which it appertains to make and use the same.

This invention pertains to a device for supporting coal and other similar drilling-machines.

The object of the invention is to provide a member known as a "grip" for seating in the coal to which the drilling-machine is secured, there being an improved means for holding the grip in place within the coal.

A further object is to provide a wedging member for use with the grip for assisting in holding the latter in a firm position.

In the drawings presented herewith and which form part of this application, Figure 1 is a perspective view of my improved grip-bar. Fig. 2 is a side elevation of a portion thereof. Fig. 3 is a top view of a portion thereof. Fig. 4 is a perspective view of a wedge used with the grip-bar. Fig. 5 is a perspective view of the wedge shown in Fig. 4 mounted on the grip-bar, the latter being shown in section, part having been removed. Fig. 6 is a cross-section of the grip-bar, showing one end of the wedge. Fig. 7 is a top view of the bar seated in a hole in a wall of coal, showing the application of the wedge for holding said bar in place. Fig. 8 is also a top view showing the wedge as in Fig. 7.

In the figures, A represents the grip-bar as ordinarily used, except that it is provided at one end with sharp projections on all four sides. The end of the bar is flared so as to have a lip B on top and at each side and a lip C at the bottom, which is much larger than the lips B, as shown. At the opposite end of the bar is pivoted a yoke D, on which the coal-drill is to be mounted. Said drill, however, is not shown, since it does not enter into my present invention; but any approved form of drilling-machine may be used with the grip-bar herein described.

In conjunction with the grip-bar I employ, as shown in Figs. 5, 6, 7, and 8, a wedge, (represented at E,) preferably, but not necessarily,

of a rounded form on its outer surface. The 55 said wedge is provided with a V-shaped groove or channel, as at F, and each face thus presented is given a shallow groove G, adapted to receive the corners of the grip-bar, as shown in Fig. 5. The groove F, as represented in Fig. 6, receives one corner of the bar, in which instance the grooves G described are not needed. The wedge, as its name implies, tapers from one end to the other, so that it may be forced into an opening and as it enters will fill said opening more and more. In use the grip-bar when it is desired to use it in a wall of coal for supporting the drilling-machine is entered in a hole bored for that purpose, as shown in Figs. 7 and 8. After the 70 bar has been pushed in as far as desired the wedge E is followed in beside it, as shown, and the result of this is that the lip B if the wedge is entered at the side of the bar is driven into the coal, as shown in Figs. 7 and 75 8, and as a matter of course the tighter the wedge is driven the more firmly the bar will be held due to the continually-increasing friction between the bar and the coal. That better results will obtain from entering the wedge 80 on top of the bar the lower lip C will be driven downward into the coal. It will be seen that by having a lip on each surface of the bar the wedge can be entered at any side or on top or even at the bottom. The shape of the hole 85 or the material in which it is cut may govern the operator as to which place the wedge shall be entered. For instance, if by chance a harder spot is found at one side of the hole or the other or above or below the hole the 90 wedge is entered on the bar at the opposite side from the said hard spot, so that when entering the wedge to hold the bar the lip B or C, as the case may be, will be forced into the hard material, with the result that a firmer 95 hold will be had. If found convenient or expedient, the wedge may also be entered at the corner of the bar, as in Fig. 6, in which case the diagonal corner will enter the coal by portions of the lips B and C.

It will be seen from the foregoing that the operator is free to enter the wedge wherever in his judgment the best results will be obtained. Though, as shown in the drawings, the wedge lies between one of the lips B and the coal, it is obvious that the bar A may be pushed farther into the hole and the wedge enter some distance behind the lips. How-

ever, this is for the better judgment of the operator when performing his work.

As a matter of fact, I do not wish to confine myself to the exact construction shown in the drawings as to the form of the wedge nor of the bar, as changes may be made that will be found desirable without sacrificing the spirit and intent of the invention.

I claim—

1. In a support of the character set forth, a bar for supporting a coal-drill at one end, the opposite end of said bar having a cutting edge at each of its four corners adapted to be forced into the coal in which the bar is to be held, and a wedge used in conjunction with the said cutting edges for entering at the side of the bar, there being a groove in said wedge for permitting a corner of the bar to enter the wedge the latter also being rounded on its outer surface in the manner set forth and for the purposes described.

2. In a support of the character described, a bar having a flaring end to form a sharp projecting corner on all of its sides, one being longer than all the others, a pivoted member at the opposite end of the bar for supporting a coal-drill, and a wedge substantially semi-circular in form and having a V-shaped groove therein opposite the rounded side, said wedge adapted for forcing one or more of the flaring corners into the coal when entered between the bar and the coal as described.

3. A support for a coal-drill comprising a bar, a series of sharp projecting lips at one end, one of which is longer than the others, a pivoted drill-supporting member at the other end, and a wedge for use in conjunction with

the bar, the same having a V-shaped groove therein for receiving a corner of the bar, and a smaller groove in each flat surface of the said V-shaped groove substantially as shown and described and for the purposes set forth.

4. A coal-drill support of the character described adapted for entering a hole in the coal comprising a bar having several faces each of which is flared at the end to provide projecting lips as described and for the purposes explained, and a wedge substantially half-round in cross-section adapted to enter the hole next to the bar at any side or at a corner thereof for forcing one or more of the lips into the coal there being a groove in the wedge for receiving the corners of the bar, there also being secondary grooves in the wedge substantially as described and shown.

5. A coal-drill support of the character described for entrance into a hole drilled into the coal, comprising a bar substantially square in cross-section, a lip projecting from the surfaces of the bar at right angles thereto one of them being longer than the others, and a wedge adapted for entrance into the hole at a corner or at one side of the support as described, said wedge being substantially half-round in cross-section and tapered, there being a V-shaped groove therein for receiving the corner of the support, there also being small similar grooves in each surface of the first groove all for the purposes explained.

In testimony whereof I affix my signature in presence of two witnesses.

WILLIAM H. CLARKSON.
